United States Patent Office

Des. 213,653
Patented Mar. 25, 1969

213,653

COMPACT

Walter Stern, New Rochelle, N.Y., assignor to Thierry
Suzanne Parfums, Inc., Miami, Fla.

Filed Jan. 4, 1968, Ser. No. 10,051

Term of patent 14 years

Int. Cl. D3—02; D28—02

U.S. Cl. D86—10

FIG. 1.

FIG. 2.

FIGURE 4 is a side view of my novel compact. The opposite side is substantially the same except that the side of the hinged container member is not seen.

I claim:

The novel design for a compact, as shown and described.
